BY *Victor J. Evans*

ATTORNEY

UNITED STATES PATENT OFFICE.

HARRY R. JONES, OF DANVILLE, PENNSYLVANIA.

RECEPTACLE.

1,245,925.

Specification of Letters Patent.

Patented Nov. 6, 1917.

Application filed May 8, 1917. Serial No. 167,216.

To all whom it may concern:

Be it known that I, HARRY R. JONES, a citizen of the United States, residing at Danville, in the county of Montour and State of Pennsylvania, have invented new and useful Improvements in Receptacles, of which the following is a specification.

This invention relates to a receptacle which is especially adapted for use as a spittoon, although the construction of the receptacle is such as to enable it to be employed as a receptacle for waste material if found desirable.

The primary object of the invention is to provide a receptacle of this character where- in the number of parts comprising the same are reduced to a minimum and so constructed that when assembled they may be readily disconnected to permit the thorough cleaning and sterilizing of the receptacle when the occasion requires.

Another object of the invention is the provision of a receptacle having detachably connected therewith a cover whereby the escape of odors and noxious gases from the receptacle may be prevented although, the lid may be raised when the occasion requires by suitable mechanism connected with the receptacle and lid and operable for this purpose.

A further object of the invention is to provide the receptacle with mechanism for raising the detachable lid which includes a foot lever, an end of which may be fulcrumed upon a support upon which the receptacle is placed, thus enabling the lid and operating mechanism therefor to be quickly disconnected from the receptacle when the occasion requires.

A still further object of the invention is to provide a receptacle having a body so constructed that the bottom thereof and a directing member within the body may be easily removed therefrom when necessary.

With these and other objects in view, the invention resides in the novel combination and arrangement of parts, which will be hereinafter described and particularly pointed out in the claim.

The preferred embodiment of the invention has been illustrated in the accompanying drawing, although no restriction is necessarily made to the precise details of construction therein shown, as changes, alterations,

and modifications within the scope of the claim may be resorted to if desired.

In the drawing:

Figure 1 is a perspective view of a receptacle constructed in accordance with the invention.

Fig. 2 is a vertical longitudinal sectional view therethrough, the cover of the receptacle being shown here in raised position in dotted lines by a mechanism operable for this purpose.

Fig. 3 is a detailed perspective view of a portion of the body of the receptacle to more clearly illustrate the construction of the ears by means of which the cover is connected with the body of the receptacle.

Fig. 4 is a detailed perspective view of the lid of the receptacle.

Like characters of reference denote corresponding parts throughout the several views in the drawing.

Referring now to the drawing in detail, the letter A designates a receptacle constructed in accordance with the invention and in which the cylindrical casing 5 formed from any suitable material, such as sheet metal, or the like, has formed therein adjacent each end a circumferentially extending bead providing the casing upon the interior thereof with annular ribs 6 and 7. The casing 5 has struck therefrom adjacent its upper end a pair of spaced and inwardly extending ears 8 each of which is provided with a bayonet slot 9, while formed within the casing 5 upon opposite sides and opening out through the lower edge thereof are slots 10.

The casing 5 is provided with a bottom 11 having a circumferentially extending and down-turned flange 12 to engage with the rib 7 and frictionally maintain the bottom 11 within the casing 5. A flared directing ring 13 is supported above the bottom 11 by the rib 6 and when the receptacle is to be used for a purpose other than a spittoon may be removed from within the casing 5.

A circular lid 13' for closing the other end of the casing 5 and adapted to rest thereon has formed thereon an extension 14 which is slotted to provide the lid with tongues 15 and 16, the tongue 16 being arranged between the tongues 15 and rolled to form a sleeve to be received between the ears 8 and engaged thereby to prevent lat-

eral movement of the lid 13' upon the casing 5. The sleeve on the cover 13' has passing therethrough a pintle pin 17, the ends of which extend beyond the ends of the 5 sleeve and are received in the bayonet slots 9 in the ears 8 to hingedly and detachably connect the lid with the casing 5.

A foot lever 18 underlying the bottom 11 of the casing 5 extends beyond the sides 10 thereof through the slots 10 and is adapted to have its forward end which is enlarged as at 19 to bear upon the support upon which the receptacle is placed, thus obviating the necessity of providing a fulcrum for 15 the lever 18 and also permitting its ready removal from the receptacle when desired. The other end of the lever 18 has connected therewith an end of a rod 20, the other end of which is forked, as at 21, and connected 20 with the tongues 15 on the lid 13', so that the last mentioned end of the lever is supported by the rod 20 and lid 13', the lever and lid being operable when pressure is applied to the enlarged end of the lever 18 to 25 turn the lid 13' about its pivotal connection with the ears 8 on the casing 5 and maintain the lid in raised position as long as pressure is maintained upon the lever 18.

Through the above described manner of

arranging the foot lever 18 beneath the bottom of the casing 5 and connecting the same with the lid 13', it will be seen that the lid and operating mechanism therefor, may be quickly connected with or detached from the casing 5 when the occasion requires and 35 that the casing 5 will serve as a guard for the lever.

From the foregoing description, taken in connection with the accompanying drawing, it is at once apparent that a receptacle has 40 been provided which comprises comparatively few parts which may be quickly disassembled to permit the thorough cleaning of the receptacle when the occasion requires and that the device, though comparatively 45 inexpensive of manufacture is highly efficient for the purpose set forth.

Having thus described the invention, what is claimed as new is:

A casing and a lid therefor, a sleeve on 50 said lid, a pintle pin passing through said sleeve and extending beyond the ends thereof, ears struck from said casing extending inwardly thereof to engage the ends of said sleeve, said ears having slots therein receiving the ends of said pin.

In testimony whereof I affix my signature.

HARRY R. JONES.
